US00D562427S

(12) **United States Design Patent** (10) **Patent No.:** **US D562,427 S**
(45) **Date of Patent:** ** *Feb. 19, 2008

(54) **BOW SIGHT**

(76) Inventor: **Bahram Khoshnood**, 2735 Two Rock Ct., Alpharetta, GA (US) 30004

(**) Term: **14 Years**

(21) Appl. No.: **29/224,790**

(22) Filed: **Mar. 7, 2005**

Related U.S. Application Data

(63) Continuation of application No. 11/034,462, filed on Jan. 13, 2005, now Pat. No. 7,082,690.

(51) **LOC (8) Cl.** **22-01**

(52) **U.S. Cl.** **D22/107**

(58) **Field of Classification Search** D22/100, D22/107, 199; 33/245; 42/132, 136, 137, 42/138, 139, 145; 124/86-90

See application file for complete search history.
